H. B. MORRIS.

MANUFACTURE OF COVERED FRAME PIECES FOR CHAIRS AND OTHER ARTICLES.
APPLICATION FILED JULY 19, 1916.

1,265,941.

Patented May 14, 1918.

Inventor

H. B. Morris

By his Attorney *Frederick Wright*

UNITED STATES PATENT OFFICE.

HAROLD B. MORRIS, OF GLENDALE, CALIFORNIA.

MANUFACTURE OF COVERED FRAME-PIECES FOR CHAIRS AND OTHER ARTICLES.

1,265,941.

Specification of Letters Patent.

Patented May 14, 1918.

Application filed July 19, 1916. Serial No. 110,217.

To all whom it may concern:

Be it known that I, HAROLD B. MORRIS, a citizen of the United States, residing in Glendale, in the county of Los Angeles and State of California, have invented certain new and useful Improvements in the Manufacture of Covered Frame-Pieces for Chairs and other Articles, of which the following is a specification.

10 It has heretofore been the practice in the manufacture of chairs in which the frame is covered with ratan, flag, grass, paper or the like to first construct the chair frame complete and then cover it by winding some parts of the frame with a covering material and covering other parts such as the seat, back and arms by interweaving the material with different parts of the skeleton frame, but I have found that the manufacture of 20 chairs can be greatly improved if the legs, rungs and similar parts of the chair are covered with the covering material before they are joined with the other parts while the seat, back and arms may be covered with 25 material in fabric form which may be machine made and securely fastened in place on the seat, back and arm frames in a novel way.

In my application for Patent No. 36,036 filed June 24, 1915, I have described and claimed some of the ways in which chairs may be thus constructed.

In some cases it is feasible to first steam or otherwise soften a frame piece to be covered, then apply the covering material thereto and then bend the covered piece. It is better in other cases to first soften the wooden frame piece, then apply adhesive thereto, then wind the covering material 30 thereon and then bend the covered piece. In other cases I have found that where the frame piece is quite long and where a sharp bend is required it is decidedly better to construct a cover for the frame piece separately and to quickly slip the covering onto the softened frame piece while it is still hot and in the best condition for bending.

My present invention relates to a method involving the formation of a tube or sleeve 50 of covering material and then applying this tube or sleeve to a softened frame piece and then bending the covered frame piece.

In carrying out my invention I may make a sleeve or tube by braiding or weaving the

covering material into tubular form, or I may form a tube of paper and surround it by covering material by winding the latter thereon, a suitable adhesive being preferably employed to cause the covering to adhere to the paper. A frame piece is steamed, boiled or otherwise heated or softened and is then coated with adhesive. Then the tube or covering material is slipped onto the frame piece and where a bend is required the bending operation is performed while the frame piece is still hot or warm. In this way the process of covering the frame piece is expedited and the cracking or breaking of the wood is largely prevented.

In the accompanying drawings:—

Figure 1 illustrates how a slip of paper is wound on an expansible mandrel to form a foundation tube.

Fig. 2 illustrates how this paper tube is covered with adhesive and then has a length 75 of covering cord wound upon it.

Fig. 3 is a view on an enlarged scale and in transverse section, illustrating the mandrel, the paper tube, the adhesive and the covering material wound on the paper tube.

Fig. 4 is a detail view in perspective showing how a tube of covering material may be formed by a braiding operation.

Fig. 5 is a view similar to Fig. 4 and shows how a suitable tube may be woven.

Fig. 6 shows how a frame piece may be grooved or indented and reinforced at the point of bending, and how it may be covered with adhesive material.

Fig. 7 is a detail view with parts broken away, showing the frame piece covered and ready for use or ready for being bent.

Fig. 8 shows how the covered frame piece is bent.

I may form a suitable sleeve by braiding 95 covering cords into tubular form, as indicated at A in Fig. 4, or I may form a sleeve by weaving the material into tubular form, as indicated in Fig. 5. Such tubes may be prepared in suitable machines.

In the remaining figures of the drawing I have shown still other ways of forming the covering sleeve.

In Fig. 1, C indicates a collapsible and expandable mandrel on which is wound a strip 105 of paper D, preferably perforated as indicated at d.

In Fig. 2 I have shown how adhesive c

may be applied to the paper tube, such adhesive filling the perforations *d* and also covering the tube. Adhesive may be applied to the paper strip before it is wound on the mandrel in which case the adhesive is preferably dried before being wound and afterward softened. Around the adhesive covered tube is wound a cord *E* of covering material of any suitable kind. When the adhesive is applied in the manner indicated it will cause the covering material to firmly adhere to the paper tube and said adhesive will pass into the indentations *d* in such manner as to form a direct connection through the paper tube between the covering cord and the frame piece to which the tube is applied. After the covering material is applied, as indicated in Fig. 2 the mandrel *C* may be collapsed and the tube withdrawn endwise therefrom and such a tube may be applied to a frame piece *F* which will then be ready for use, or in case the frame piece is to be bent the latter should be first softened, then have the tube applied to it and the bending operation should be then performed. Preferably the frame piece is grooved or formed with indentations or recesses, as indicated at *f* in Fig. 6. This is for the purpose of holding some of the glue or adhesive as otherwise when the sleeve is slipped on to the frame piece most of the glue might be wiped off. In Fig. 6 I have shown adhesive applied to the stick or frame piece before the sleeve is slipped onto it but in some cases it is not necessary to coat the frame piece with adhesive as sufficient adhesive will be held and supplied by the tube. If the frame piece has been steamed, boiled or otherwise heated it will sufficiently soften the adhesive in the sleeve to cause the sleeve to adhere to the frame piece.

In Fig. 6 I have illustrated how the frame piece may be reinforced or strengthened where sharp bends occur. This is done by inlaying small pieces of sheet metal *f* and attaching these pieces to the frame piece by securing devices *f*.

When the frame piece is to be bent it is first steamed, boiled or otherwise heated and softened, then if necessary glue may be applied directly to it, as indicated in Fig. 3, and then the sleeve of covering material, whether of the kind shown in Fig. 7 or of the kind shown in Figs. 4 or 5, is quickly slipped onto the frame piece while it is still hot, and then the frame piece is bent in the manner indicated in Fig. 3 and held until it assumes permanently the bent condition. It will thus be seen that while in some conditions it is practicable to cover a frame piece by holding it in a winding machine and winding the covering material thereon it is much better in other cases to apply the covering material even more quickly to the frame piece by first forming the cover by a

separate operation, then quickly slipping it on a frame piece while the latter is still hot and soft and then bending the covered piece.

I claim as my invention:

1. The method herein described of preparing a frame piece for chairs and other articles, which consists in attaching to the frame piece a piece of sheet metal where a bend is to be made, softening the piece, applying covering material thereto and then bending the covered piece. 70

2. The method herein described of preparing a frame piece for chairs and other articles, which consists in applying a piece of sheet metal where a bend is to be made, softening the piece, applying thereto a sleeve of covering material and then bending the covered piece. 80

3. The method herein described of preparing a frame piece for covered chairs and other articles, which consists in softening the piece, applying thereto a previously formed sleeve of flexible covering material resembling the covering of the finished article, and then bending the piece, thereby causing the flexible sleeve to assume a corresponding form. 85

4. The herein described method of preparing a frame piece for covered chairs and other articles, which consists in softening the frame piece, slipping a previously formed sleeve of absorbent covering material endwise thereon, causing the sleeve to adhere to the frame piece by a suitable adhesive, and then bending the frame piece while in a soft bendable condition, thereby causing the sleeve of covering material to assume a corresponding form. 95

5. The method herein described of preparing a frame piece for chairs and other articles, which consists in preparing a covered sleeve of flexible absorbent material, heating and softening the frame piece to be covered, slipping the sleeve endwise on the frame piece while it is still in a soft bendable condition, causing the covering to adhere to the frame piece, and then bending the frame piece, thereby causing the covering sleeve to assume a corresponding form. 105

6. The herein described method of preparing a frame piece for covered chairs and other articles, which consists in preparing a sleeve of flexible absorbent material corresponding to that of the finished article, heating and softening the frame piece to be covered, slipping the sleeve endwise on the frame piece while it is still in a soft bendable condition, causing the covering to adhere to the frame piece, and then bending the covered frame piece. 115

7. The herein described method of preparing a frame piece for chairs and other articles, which consists in attaching to the frame piece a strip of sheet metal where a bend is to be made, softening the piece, 120

applying covering material thereto and then bending the covered frame piece. 125

applying the covering material thereto, causing the covering material to adhere to the piece, and then bending the covered piece while still in a soft bendable condition.

8. The method herein described of preparing a frame piece for chairs and other articles, which consists in attaching to the frame piece a sheet of metal where a bend is to be made so that the metal occupies a position around the outer circumference of the bend, softening the piece, applying covering material thereto, and then bending the covered piece.

10. The method herein described of preparing a frame piece for chairs and other articles, which consists in applying a piece of sheet metal where a bend is to be made,

softening the piece, applying thereto a flexible sleeve of covering material, and then bending the covered piece.

10. The method herein described of preparing a frame piece for chairs and other articles, which consists in reinforcing the portion where a bend is to be made, softening the reinforced portion, applying to said portion a flexible sleeve of covering material, and then bending the piece, thereby causing the sleeve of covering material to assume a corresponding form.

In testimony whereof, I have hereunto subscribed my name,

HAROLD B. MORRIS.
